No. 655,354.

Patented Aug. 7, 1900.

W. SCOTT.
PRINTING MACHINE.

(Application filed Oct. 20, 1891.)

(No Model.)

UNITED STATES PATENT OFFICE.

WALTER SCOTT, OF PLAINFIELD, NEW JERSEY.

PRINTING-MACHINE.

SPECIFICATION forming part of Letters Patent No. 655,354, dated August 7, 1900.

Application filed October 20, 1891. Serial No. 409,341. (No model.)

To all whom it may concern:

Be it known that I, WALTER SCOTT, a citizen of the United States, and a resident of Plainfield, in the county of Union and State of New Jersey, have invented certain new and useful Improvements in Printing-Machines, of which the following is a specification.

The present invention relates to web-perfecting presses, and more especially to mechanism for causing register of the webs from a plurality of presses, the principal objects of the invention being to secure ready and accurate compensation for faulty registry of the printed matter on the webs and also to permit of the slackening up of the webs between the printing-press and the folding mechanism in case such slackening up should be required or necessary and the restoration of the webs to the exact registry whenever the slack is taken up again.

To these and other ends the invention includes features of construction and combinations of devices hereinafter described, and more particularly pointed out in the appended claims.

The preferred form of the invention is illustrated in the accompanying drawings, forming part of this specification, in which—

Figure 1 is a diagrammatic side elevation 30 of the press. Figs. 2, 3, and 4 are detail views. Fig. 5 is a diagrammatic view of a modification. Figs. 6 and 7 illustrate the placing of sheets, and Fig. 8 associating bars.

Three presses are shown arranged one above another, the web P for the upper press leading about rolls 10, 11, and 12 in its way to and from the said upper press, the web Q leading about rolls 10^b, 11^a as it passes from and to its press, and the web R leading about rolls 10^b, 11^b, and 12^b as it moves to and from its press. The web is supported between the rolls 11 and 12 by tapes 13, which run upon rolls or pulleys 14, 15. The web Q is supported after it leaves the roll 11^a by tapes 19, which run upon rolls 18 and 20. The web R is supported between the rolls 11^b and 12^b by tapes 22, running upon rolls or pulleys 23, 24, and r. The web r passes from the roll 12^b between cutting-cylinders 25, 26 of a size adapted 50 to cut half-length sheets from the said web, and said half-length sheets are carried out upon tapes 27, running upon rollers 28, 29 and

an adjustable roll 30. Fixed guides 31, 32 above and below the tapes 27 prevent the sheets from rising therefrom. The roll 30 is carried by adjustable arms 33. The half-sheets from the web R are run by the tapes 27 between cutting and folding cylinders 74, 75 and are there associated with the webs P, Q. The cylinders 74, 75 are provided with cutting-blades 76 and grooves 77 for severing full-length sheets from the webs P, Q. The cylinder 74 is provided with a tucking-blade 78, and the cylinder 75 is provided with groove 81 for coaction with said tucking-blade and 60 with sheet 82 for nipping the creased sheets, said tucking-blade and groove 81 being opposite the cutting devices of the said cylinders 74, 75. The sheets cut by the cylinders 25, 26 are half the length of the sheets cut by the 70 cylinders 74, 75 when the lower press is running at half the speed of the two upper presses, and the half-sheets may be associated with the full-length sheets in the manner indicated in Fig. 6 or in that indicated in Fig. 75. In both Figs. 6 and 7, m, m' indicate outer margins of the print, and c, c' indicate inner margins of the print, while 1, 2, and 3 indicate the sheets cut from the webs A, Q, R, respectively. In both figures, 109 indicates 80 the line of fold by the tucking-blade 78 and groove 81, and 112, 113 represent the edges cut by the blade 76 and groove 77. The cylinders 25 may be so timed as to secure that the front margin of the sheet 3 shall overlap 85 the crease at 109, as indicated at 110 in Fig. 6 or as indicated at 111 in Fig. 7. The grippers 82 carry the sheets around until the time the tucker-blade 80 coacts with the groove 84 and grippers 85, but fold the sheets again 90 transversely and to transfer them to the cylinder 83, whence they are delivered between the cylinder 83 and roller 86 upon tapes 87, which run about the cylinder 83 and rolls 86, 88 and pass to a folder M, whence they are 95 delivered.

The web P passes about rollers 41, 42, and 16 and to the cylinder 75, and the web Q passes about roller 18 directly to said cylinder 75. The rolls 41, 42 are carried, respectively, 100 by arms 43, 44, which project from a rock-shaft 45, journaled in the framework of the machine, the arms 43, 44 being so placed that the web in passing from the upper side of roll

41 to the under side of roll 42 does not touch the shaft. The shaft 45 is provided with an arm 46, which is adjusted as hereinafter described. Paste is applied to the web P by a 5 revolving blade 17, carried in arms from a rotating shaft 47 and taking paste from a roller 48, running in a paste-fountain 49. The shaft 47 has a gear 50 thereon, which meshes with the gear 51 to drive the fountain-roller 10 48. The shaft 47 also has a gear 58 thereon, which meshes with the gear 57 to a train of gearing 57 60 61 62, coming from the middle press. A gear 59 on a shaft 54 meshes with the gear 57 to rotate the shaft 54. Paste is 15 applied to the web Q by a revolving blade 21, carried in arms from the shaft 54. The shaft 54 has a gear 55 thereon, which meshes with a gear 56 on the shaft of the fountain-roller 52, which runs in a paste-fountain 53, 20 the blade 21 taking paste from the roller 52. A gear 90 connects the gear 57 with the cylinder 55, and a gear 91 connects the cylinder 74 with the pulley 29 for running the tapes 27. 25 91^a indicates a driving-pulley intermediate the cylinder 26 and the tape-pulleys 24 for driving the latter. The cylinder 26 is driven by a train of gearing 93 94 from the lower press. 92 indicates the folding and cutting apparatus of the cylinders 25 26.

For the purpose of driving the lower press at the same speed as or at half the speed of the two upper presses the shaft 35 of the second impression-cylinder of the lower press 35 has two gears 36 37 fast thereon, and a shaft D is provided with adjustable gears 38 39, which are held from rotating independently of the shaft D by means of a feather and groove or by means of a groove and set-bolt 40. 40 34 is a gear intermediate the upper and middle presses.

The roller 18 is carried by arms 63 from a rock-shaft 64, and the shaft 64 has an arm 65, preferably of resilient material.

45 66 indicates a toothed catch bar or arm which is journaled at 67 to an arm 73 in the fixed framework of the machine. The arm 66 is provided with lugs 71 72 at opposite sides of the arm 73, and the lugs 71 72 are provided 50 with adjusting clamping-screws 69 70 for co-action with the opposite sides of the arm 73, whereby the arm 66 may be swung about its pivot 77 to move a tooth 68 thereof into various positions. The arm 65 is drawn upwardly 55 by the tension of the web Q on the roller 18, and its upward motion is arrested by the tooth 68 on the arm 66. By springing out the arm 65 it may be disengaged from the tooth 68 and the roller 18 may be lowered to slack

60 up the web Q. Upon returning the arm 65 into engagement with the tooth 68 the web Q is brought back to its proper position and the registry thereof with the webs P R is not disturbed. The arm 46, above named, may 65 be held in position by identical means and be operated to slack up the web P at the take-up U and be returned to engagement with its

catch, thus restoring the registry of the web P. Some of the advantages of this construction of the take-ups are that the take-up permits of ready and accurate compensation for faulty registry of the printed matter on the webs by proper manipulation of the screws 69 70; also, as above stated, after proper registry has been secured the arm controlling the take-up and let-off may be moved away from the catch therefor and be sprung outward and be moved above the tooth 68 for any purpose, and thereafter be returned to its position under said tooth without in any wise disturbing the registry.

The printing-presses imprint double-width webs, and the sections of the web, as P' P², may be associated with each other by means of parallel turning bars 114 115, as indicated 85 in Fig. 8.

When the lowest press is run at the same speed as the upper presses, the web R is taken around a roller 117 and not between cutting-cylinders 25 26 on its way to the cylinder 74 75. 90

The blade 80 may be fixed to the cylinder 75, and the cylinder 76 may have a flattened portion 79 to permit the blade 80 to pass thereby. In this case the blade 76 may only 95 perforate the paper and the blade 80 serve to tear the sheets from the web at the line of perforation.

In the modification illustrated at Fig. 5 the cylinders 74^a 75^a have their positions inverted and the cylinder 74^a is provided with a 100 cutting-blade 76^a and with a creasing-blade 78^a and with pins 96, while the cylinder 75^a has cutting-groove 77^a and a tucking-groove 81^a and grippers 82^a. The cylinder 75^a is grooved at 97 to receive the stripping-guides 105 98, and the sheets are delivered from the cylinder 75^a between said guides 98 and tapes 108, running upon rollers 107. The cylinders 25^a 26^a are arranged to sever half-length sheets from the web R, 92^a indicating the cutting-blade, and 95 the corresponding groove in the cylinder 26^a. a indicates pins in the cylinder 26^a, which is grooved at 105 to receive strippers 104, between which strippers and guides 103 the sheets are carried out onto 110 the tapes 27^a, which run upon pulleys 28^a 29^a. 99 is a set of tapes running upon rollers 100 101 above the tapes 27^a. 106 indicates guides which support the sheet between the pulleys 29^a and the cylinder 75^a. 102 indicates a gear 115 intermediate the cylinder 26^a and the pulleys 100. 102

By leading the web P from the second impression-cylinder of the upper press to the first impression-cylinder of the middle press, 125 as indicated by the line X, and from the second impression-cylinder of the middle press to the first impression-cylinder of the lower press, as indicated by the line Z, a plurality of impressions upon each side thereof may be 130 secured.

What I claim is—

1. The combination with a rock-shaft, a take-up borne by arms thereon, and a lever

thereon to operate the same, of an adjustable toothed holder on the frame for said lever, and screws acting on said holder to move the same for adjustment, whereby the take-up 5 can be accurately adjusted to position, and then be moved out of and into position at will, substantially as described.

2. The combination of a number of printing-presses arranged one over another and 10 each perfecting its own web, a folding and cutting mechanism to which all the webs are taken, web take-up or register roll or rolls for one or more of said webs, a rock-shaft and arms therefrom for each take-up for carrying 15 said rolls, a resilient or flexible arm on each rock-shaft, and a stop for each of the last-named arms for limiting the motion thereof in one direction and from which said arm may be freed by being flexed or sprung and 20 so be moved freely to slack up the corresponding web and be returned to position without disturbing the register of the webs, substantially as described.

3. The combination of a number of printing-presses arranged one over another and 25 each perfecting its own web, a folding and cutting mechanism to which all the webs are taken, web take-up or register roll or rolls for one or more of said webs, a rock-shaft and arms therefrom for each take-up for carrying 30 said rolls, a resilient or flexible arm on each rock-shaft, and an adjustable stop for each of the last-named arms for limiting the motion thereof in one direction and from which said arms may be freed by being flexed or 35 sprung and so be freed to move to slack up the web and be returned to position without disturbing the register of the webs, substantially as described.

Signed at New York, in the county of New 40 York and State of New York, this 19th day of October, A. D. 1891.

WALTER SCOTT.
